DEXTER H. CHAMBERLAIN, OF WEST ROXBURY, MASSACHUSETTS.

Letters Patent No. 83,461, dated October 27, 1868.

ELEVATOR FOR BUILDINGS.

The Schedule referred to in these Letters Patent and making part of the same.

To all whom it may concern:

Be it known that I, DEXTER H. CHAMBERLAIN, of West Roxbury, in the county of Norfolk, and State of Massachusetts, have invented certain Improvements in Elevators for Buildings, &c., of which the following is a full, clear, and exact description, reference being had to the accompanying drawings, making part of this specification, in which—

Figure 1 is a perspective view of an elevator with my improvements applied thereto.

Figure 2 is a vertical transverse section through the centre of the same, representing the position of my improvements when the carriage is in motion.

Figure 3 is a vertical section representing the position of my improvements when they prevent the descent of the carriage on the parting of the "fall."

Figure 4, detail to be referred to.

In the ordinary construction of elevators for raising and lowering merchandise in buildings, the arresting-devices act directly upon the guide or way upon which the platform slides, which construction is objectionable for the following reasons, viz.:

Owing to the guide or way being lubricated to relieve friction in hoisting, the arresters or stops do not act the instant of the parting of the "fall," and before they are thrown in contact with the guide, the weight has acquired sufficient momentum to overcome the friction applied by the stops, thus thrusting the post and slide out of position, and frequently breaking the stops and cross head to which they are attached, thereby allowing the carriage to be precipitated to the bottom, endangering the lives of those upon it.

To provide a means (reliable at all times) for arresting the descent of the carriage immediately on the parting of the "fall," is the object of my invention, which consists in a pair of rods, ropes, or chains passing down vertically through the cross-head of the carriage, near its outer ends, each rod, or its equivalent, being independent of the guide or way, and being forcibly pressed by a wedge (either serrated or not) at the instant of the parting of the "fall," the degree of friction thus created being sufficient to overcome the gravity of the ascending or momentum of the descending weight, thereby securely suspending it, without danger to the life or limb of persons, or of damage to goods thereon.

To enable others skilled in the art to understand and use my invention, I will proceed to describe the manner in which I have carried it out.

In the said drawings, A represents the floor of a building; B B, vertical posts proceeding up along the walls of the enclosed space in which the carriage is to move. Secured to the inner face of each of these posts is a guide or way, a, upon which slide the cross-head C at the top and platform D at the bottom of the carriage. b b are iron rods which connect the

platform with the cross-head, thus serving to brace and steady it when carrying its load.

Across the top of the posts B B extends a horizontal beam E, through each end of which, and each end of the cross-head C and platform D, passes an upright circular rod of metal, e, the lower end of each rod being secured by a screw-nut to the under side of the floor A.

At each end of the cross-head C, where the vertical rod e passes through it, is formed an inclined recess for the reception of a correspondingly-shaped block or wedge, d, the outer surface of which, next the circular rod e, is concave and serrated, (see fig. 4,) so as to fit snugly around and securely hold on to it, when the wedge is brought in contact with it on the breaking of the "fall" F, by mechanism now to be described.

G is a vertical pin passing through the centre of the cross-head C, the upper end of the pin being enlarged and provided with an eye, e, into which is fastened the lower end of the "fall" F. The lower end of the pin G extends down below the bottom of the cross-head, and has a nut, f, screwed thereon, and the lower portion of the cross-head C is provided with an enlarged circular recess, g, around the pin, for the reception of a spiral spring, h, the upper end of which presses against the under side of this recess, while the lower end of the spring rests upon a washer, i, surrounding the shank of the pin G, and resting upon the inner ends, k, of two arms or levers, H, bent in the form shown, and pivoted, at l, on screws passing through holes m, to allow the levers to rock slightly thereon.

The inner ends of the arms or levers H unite around and enclose the vertical pin G, while the outer end of each of these levers is bifurcated so as to fit into a notch, n, formed in the bottom of each of the wedges d. (See figs. 2, 3, and 4.)

It will thus be seen, from the foregoing description, that when the carriage is being raised or being lowered by the application of power to the "fall," the inner ends of the levers H are pressed up by the screw-nut f, thereby compressing the spring h, while the outer ends of these levers H are rocked downward, carrying with them the wedges d into the position seen in fig. 2, the friction between the serrated surfaces of the wedges d and the cylindrical surfaces of the rods e being relieved, and thus offering no resistance to the upward or downward passage of the elevator.

Should, however, the "fall" F part, the spring h is immediately liberated, and by its recoil presses down the inner ends of the levers H, consequently throwing up their outer ends so as to raise the wedges into the position seen in fig. 3, the outward pressure on the wedges creating sufficient friction between their serrated surfaces and those of the rods as to instantaneously overcome the momentum or gravity of the load

upon the elevator, and preclude the possibility of its being precipitated below. By my improved construction, the guide or way *a* is not subjected to a lateral strain incident to the old construction; and the derangement and breakage of the parts, which have heretofore caused loss of life and limb and destruction of goods, are thereby avoided.

Claims.

What I claim as my invention, and desire to secure by Letters Patent, is—

The rods *c c*, or their equivalents in combination with the wedges *d d*, or their equivalents, and the cross-head *C*, substantially as and for the purpose set forth.

Also, the levers *H H*, spring *h*, and pin *G*, in combination with the wedges *d d* and the rods *c c*, for the purpose described.

DEXTER H. CHAMBERLAIN.
